UNITED STATES PATENT OFFICE

2,202,721

TIME SWITCH ALARM

Herbert H. Andersen, Beverly, Mass., assignor to
General Electric Company, a corporation of
New York

Original application February 24, 1939, Serial
No. 258,219. Divided and this application No-
vember 7, 1939, Serial No. 303,256

1 Claim. (Cl. 161--23)

This application is a division of my application filed February 24, 1939, Serial No. 258,219 for a Time switch. Said prior application describes a time switch particularly designed for timing 5 the operation of domestic electric ranges and this type of switch has often been referred to as a range timer.

Associated with such switch and controlled by the same timing motor is a timer signal which 10 the user of the switch may set to give a signal at a predetermined time or after a predetermined time interval. Such signal is useful for signaling the end of short time intervals and it is to such invention that this divisional application relates. 15 It is the object of my invention to provide a reliable, simple and inexpensive adjustable time signal suitable for use in connection with range timers.

The features of my invention which are believed to be novel and patentable will be pointed out in the claim appended hereto. For a better understanding of my invention, reference is made 20 in the following description to the accompanying drawing in which Fig. 1 is a perspective view 25 of the operating features of my time signal shown in combination with a time switch mechanism, both being operated by the same timing motor, and Fig. 2 is a perspective face view of a range timer equipped with my time signal.

30 It is not essential to an understanding of my invention that the details of the time switch mechanism be fully described herein, and I will only refer to such parts thereof in this application as cooperate in the use of the time signal.

35 At 10 is a synchronous electric motor or other suitable timing device. Its field coil 11 is energized through the line wires 101 and 95 which furnish energy to the electric switch contacts. It is to be understood that the motor is continuously 40 energized and is intended to operate continuously. The part designated 12 represents a gear casing containing reduction gearing between the motor rotor and the gear train indicated at 14. Included as a part of the range timer is a clock 45 driven by the timing motor and with which the setting of my time signal may be correlated.

The minute and hour hands of the clock are designated 16 and 17 and these hands are driven with respect to the conventional clock dial 50 through the gear train designated 14. 13 represents the minute hand shaft, which is connected to the gear train 14 through a friction clutch 15 to permit setting of the clock. The back gears between the minute and hour hand shafts are 55 shown at 20, 21 and 22. The clock hands may

be set by turning the thumb nut 63. This thumb nut is connected to the hour hand shaft 18 through gears 61, 50a and 22.

As a convenience to the housewife and cook I have provided a signal bell 78 operated by the timer mechanism by means of which the desired ending of short cooking periods or other short time reminder periods may be signaled. For this purpose a shaft 79 may be connected in driving relation with the timer motor through clutch 80, 10 gear 81 and gear 82. Shaft 79 is movable endwise. It is biased forward by a spring 83 which is also a bell clapper member and which bears against the rear end of shaft 79. Near the front end of shaft 79 it has fastened to it an eccentric 15 finger 84 and a pointer knob 85. Pointer knob 85 indicates on a minute dial 86 and finger 84 cooperates with the front clock plate 64 and in the zero minute indicating position of pointer 20 85, finger 84 registers with an opening 87 in the clock plate and in such position will enter the opening under tension of spring 83 and move shaft 79 forward, demeshing gear 81 from gear 82 and the clapper 83 will strike bell 78 and give a signal. In the position of the parts shown shaft 25 79 has been pushed to the rear to disengage arm 84 from slot 87. Also, knob 85 has been turned to indicate 30 on dial 86. The shaft 79 is thus held in this rearward position by reason of finger 84 bearing against the rear of plate 64. In such position 30 gears 81 and 82 are in mesh and shaft 79 is driven clockwise, in this case, at the rate of one revolution per hour. Spring 83 is under tension. In thirty minutes finger 84 will register with opening 87, shaft 79 will quickly move forward, 35 gear 81 will be demeshed from gear 82 and the upper end of clapper spring 83 will strike the bell, giving a signal. This mechanism then remains out of operation until reset by pushing in on knob 85 and turning it to the left to the position desired. Shaft 79 may thus be turned when pushed to the rear and gears 81 and 82 are in mesh by reason of slip friction clutch 80.

40 This is a convenience for timing short operations which need not necessarily have to do with cooking but which may have to do with cooking operations that are too short or too exacting to be left to automatic switch operation. For example, suppose eggs boiled exactly four minutes are desired. The time required for the water to 45 come to a boil is indefinite since it depends, for example, on the original temperature of the water. As soon as the water starts to boil, the eggs are put in and pointer knob 85 set at four on dial 86. In exactly four minutes the bell will 50 55

sound, signaling the end of the four minute period. Where desired the shaft 79 may be geared to rotate faster than one revolution per hour and the dial 86 graduated accordingly for greater accuracy in setting and timing. This signaling convenience, while operated by the same timing mechanism as the time switch and clock, does not interfere with their independent or simultaneous operation.

10 A front view appearance of this timer in its casing is represented in Fig. 2 and is covered by Design Patent 110,906, August 16, 1938, to Patten.

What I claim as new and desire to secure by Letters Patent of the United States is:

15 A timer, a clock motor for driving said timer, a bell signal for signaling short timing periods comprising a rotary and axially movable shaft, a turning knob and indicator pointer on the front end of said shaft, a time graduated dial on which

said pointer indicates, a supporting plate through which said shaft extends, a member secured to said shaft behind said plate having a finger eccentric to said shaft, an opening in said plate at one point in the arc of travel of said finger with which said finger registers in one rotative position corresponding to a zero time indication of said pointer on said dial, a spring fixed at one end and pressing forward against the rear end of said shaft and serving to press said finger against 10 said plate and into said opening when the finger registers therewith, a bell, a bell hammer on the free end of said spring, said spring also serving as a bell clapper to strike said bell when the shaft is moved forward at its zero time indicating 15 rotary position, a gear rotatively mounted on said shaft driven by said motor and a slip friction clutch between said gear and shaft.

HERBERT H. ANDERSEN.
